UNITED STATES PATENT OFFICE

2,633,635

HAIR TRIMMER

Samuel N. North, Asheville, N. C.

Application May 31, 1949, Serial No. 96,223

1 Claim. (Cl. 30—30)

1 This invention relates to hair trimmers.

An object of this invention is to provide a hair trimmer embodying a separable holder and a double edge blade which will permit the trimming of the ends of the hair in addition to the close cutting of the hair around the edges.

Another object of this invention is to provide a hair trimmer embodying a holder formed of face abutting flat members having toothed blade holding members extending therefrom, with an improved means for locking the members together.

A further object of this invention is to provide an improved holder for a double edge blade whereby the blade may be stropped or honed.

With the above and other objects in view, my invention consists in the arrangement, combination and details of construction disclosed in the drawing and specification, and then more particularly pointed out in the appended claim.

In the drawing,

Figure 1 is a plan view of a hair trimmer constructed according to an embodiment of this invention.

Figure 2 is a sectional view taken on the line 2—2 of Figure 1.

Figure 3 is a sectional view taken on the line 3—3 of Figure 1.

Figure 4 is a fragmentary plan view of the inner end portion of the handle.

Figure 5 is a fragmentary plan view of an inner end portion of the keeper notch carried by one portion of the handle.

Figure 6 is a plan view of a blade stropping device constructed according to an embodiment of this invention.

Figure 7 is a detail side elevation of the device shown in Figure 6.

Referring to the drawing and first to Figures 1 to 5 inclusive, the numeral 10 designates generally a handle having disposed at the forward end thereof a blade holder generally designated as 11. The handle 10 includes a body 12 which is shaped on the marginal edge portions thereof in a manner to conveniently fit into a hand, and the body 12 has extending from the rear thereof a finger 13 formed with a concave edge 14.

The body 12 includes one part 15 of the holder 11, comprising a plate or flat member which is formed with spaced teeth 16 along one edge thereof, and a second series of spaced teeth 17 along the opposite edge thereof. The handle 10 also includes a second body member 18 shaped similar to the body member 10, and provided at the rear portion thereof with a keeper notch 19.

2 within which a locking lug 20 carried by the forward or inner end of the finger is adapted to releasably engage.

The body 18 is formed at its forward portion with a blade clamping member 21 which is provided with an elongated slot 22 extending lengthwise thereof, within which an elongated locking member 23 which is fixed to the clamping member 15 is adapted to engage. The locking member 23 includes a lug 24 which engages over the outer side of the clamping member 21 at the forward end of the locking member 23 so as to hold the clamping member 21 tightly against the holder or clamping member 15.

15 The finger 13 is provided with a locking lug 25 adapted to engage over the outer side of the handle forming member 18, being positioned above the locking member 20 so as to hold the handle forming member 18 in face abutting relation to the handle forming member 12. The clamping member 21 is formed along one edge thereof with teeth 26 which are complementary to the teeth 16, and additional teeth 27 are disposed along the opposite edge of clamping member 21 and are complementary to the teeth 17.

20 A double edge razor blade 28 is adapted to engage between the two clamping members 15 and 21, and one edge 29 of the blade 28 is adapted to project slightly beyond the outer ends of the teeth 16—26. The opposite edge 30 of the blade 28 is disposed inwardly from the outer ends of teeth 17—27, these teeth being substantially longer than the teeth 16—26. The inwardly disposed edge 30 is designed for trimming the hair relatively long, whereas the edge 29 which projects slightly beyond the teeth 16—26, is designed for giving a relatively close trim.

25 Referring now to Figures 6 and 7, there is disclosed a holder for use in stropping or honing a razor blade such as a double edge blade. A holder comprising a handle generally designated as 31 is provided, which includes a pair of handle forming members 32 and 33 disposed in face abutting relation. The handle forming member 32 is relatively longer than the handle forming member 33 and an abutment 34 is formed on the handle forming member 32 against which the rear end of the handle forming member 33 is adapted to engage. The handle forming member 32 has a locking lug 42 projecting forwardly from the shoulder 34, and the handle forming member 33 is provided with a keeper notch 36 similar to keeper notch 19, within which the lug 42 is adapted to engage.

30 The holder 31 also includes a blade clamping

3

member 37 integral with the handle forming member 32, and a blade clamping member 38 integral with the handle forming member 33. The clamping member 38 is provided with an elongated slot 39 through which a locking bar 40 carried by the clamping member 37 is adapted to engage. The locking member 40 projects forwardly beyond the forward end of slot 39, as indicated at 41, so that the two clamping members 37-38 may be firmly locked together.

Locking lug 42 extends forwardly from handle member 32 for engagement over the handle member 33 so that the two handle members 32 and 33 will be firmly locked together. The handle member 33 adjacent the forward edge thereof is provided with a fingernail notch 43 so that a finger nail may be inserted between the two handle members 32 and 33 in order to slightly bend handle member 33 and thereby raise the blade clamping member 38 above the locking member 40 at the rear end of the latter. Bending of handle member 33 will also pull the rear end of this member from the locking lug 35 so that the two handle members and the blade clamping members may be disengaged from each other. A double edge blade 44 is adapted to be clamped between the two clamping members 37-38, with only one edge thereof projecting beyond the adjacent edges of the clamping members 37-38, as shown in Figure 6.

I do not mean to confine myself to the exact details of construction herein disclosed, but claim all variations falling within the purview of the appended claim.

What I claim is:

A hair trimmer comprising a pair of blade

4

clamping members, each formed with teeth along the opposite longitudinal edges thereof, an elongated bar fixed to the inner face of one of said members and extending parallel with the length thereof, the other of said members having an elongated opening within which said bar engages, a locking lug carried by one end of said bar and engageable over the outer side of said other member, an elongated handle projecting from each member, a finger projecting from the end of one handle opposite its associated clamping member, the extending end of said finger forming a shoulder against which the inner end of the other of said handles is adapted to abut, and a handle locking lug carried by said finger engageable over the inner end of said other handle whereby to lock said handles in face abutting relation, said second locking lug cooperating with said first locking lug in locking said members in blade clamping position.
